2 Sheets-Sheet 1

A hand-drawn diagram of a cell. It is an oval shape with a thick black border. Inside, there is a smaller circle representing the nucleus, and the surrounding area is labeled 'cytoplasm'. The number '16' is written to the left of the cell.

STATIONARY WHEEL ORNAMENT

John G. Parks, Chicago, Ill.

Application May 24, 1938, Serial No. 209,801

3 Claims. (Cl. 40—129)

This invention appertains to new and useful improvements in ornaments for vehicles, and more particularly to a wheel ornament which will remain stationary as the wheel rotates.

- 5 An important object of the invention is to provide a wheel ornament which can be easily installed on the wheels of a vehicle and which will remain stationary while the wheels are rotating in carrying the vehicle.
- 10 Other objects and advantages of the invention will become apparent to the reader of the following specification.

In the drawings,

Figure 1 represents a fragmentary front elevational view of the wheel partly broken away to disclose the installation of the invention.

Figure 2 is a fragmentary outside elevational view of the wheel and ornament.

Figure 3 is a fragmentary detailed sectional view.

Figure 4 is a fragmentary perspective view of the ornament.

Figure 5 is a sectional view taken substantially on line 5—5 of Figure 1.

25 Figure 6 is a sectional view on line 6—6 of Figure 3.

Figure 7 is a perspective view of the ornament carrier.

Figure 8 is a perspective view of the packing element.

Referring to the drawings, wherein like numerals designate like parts, it can be seen in Figure 1 that the numeral 5 represents the hub of the wheel 6 provided with the hub cap 7.

35 Numeral 8 represents the wheel spindle which is threaded to accommodate the nut 9. In carrying out the present invention, the ring 10 is employed, the same having the key 11 which fits into the usual key slot of the spindle, the spindle of course, as is well known, being stationary and not turning with the wheel 6. This holds the ring 10 stationary. Extending outwardly from the ring 10 is the arm 12, the arm being bent downwardly as at 13 and then outwardly, co-

40 axially with the spindle 8. A spindle cap 14 engages over the outer end of the spindle and nut 9 and through the cap 14 the co-axially disposed portion 15 extends, an annular packing member 16 being disposed around this portion 15 and 45 against the outer portion of the cap 14 to prevent leakage of grease from the cap 14.

A lug 17 is provided on the outer end portion of the portion 15 of the arm 12 and engages into the bayonet slot or slots 18 of the barrel 19 which carries the ornament such as an arrow 20, the barrel 17 extending through an opening in the 5 central portion of the main hub cap 7 with the ornament 20 at the outside. There is preferably a spring 21 located in the barrel 19 to bear against the outer end of the portion 15 of the arm 12 so as to retain the pins or lugs 17 against displacement from the bayonet slots 18.

While the foregoing specification sets forth the invention in specific terms, it is to be understood that numerous changes in the shape, size, and materials, may be resorted to without departing 15 from the spirit and scope of the invention as claimed hereinafter.

Having described the invention, what is claimed as new is:

1. In combination with the stationary spindle 20 of a wheel, a member secured to the spindle, an arm extending from the member on the spindle, an ornament, said ornament being detachably connected with the arm, said detachable connection consisting of the provision of a barrel on 25 the ornament having a bayonet slot therein, and a pin on the arm engageable into the bayonet slot.

2. In combination with the stationary spindle 30 of a wheel, a member secured to the spindle, an arm extending from the member on the spindle, an ornament, said ornament being detachably connected with the arm, said detachable connection consisting of the provision of a barrel on the 35 ornament having a bayonet slot therein, a pin on the arm engageable into the bayonet slot, and spring means in the barrel for preventing displacement of the adjacent end of the arm.

3. A stationary ornament for vehicle wheels comprising a member secured to the stationary 40 spindle of the wheel, an arm extending from the member on the spindle, an ornament, said ornament being detachably connected with the arm, said detachable connection consisting of a barrel having a bayonet slot therein, a pin engageable 45 into the bayonet slot and spring means in the barrel for preventing displacement of the barrel and arm from each other.
